E. D. THOMPSON.

Car Coupling.

No. 105,278.

Patented July 12, 1870.

INVENTOR:

Edward D. Thompson

United States Patent Office.

EDWARD DAVIS THOMPSON, OF LAWRENCE, KANSAS.

Letters Patent No. 105,278, dated July 12, 1870.

IMPROVEMENT IN CAR-COUPINGS.

The Schedule referred to in these Letters Patent and making part of the same.

To all whom it may concern:

Be it known that I, EDWARD DAVIS THOMPSON, of Lawrence, in the county of Douglas, in the State of Kansas, have invented certain Improvements in Self-adjusting Car-Couplers; and I do hereby declare that the following is a full, clear, and exact description of the construction and mode of operation of the same, reference being had to the annexed drawing making part of this specification.

The object of this invention is to provide a coupling for railroad cars which shall be self-acting, durable, and simple in construction and operation.

It consists in the construction and arrangement of devices, as hereinafter more fully described.

In the accompanying drawing—

Figure 1 is a side view of a car-truck with my coupling attached.

Figure 2 is a side view of my coupling with the bumpers engaged.

Figure 3 is a side view of the same with the draw-heads engaged.

Figure 4 is a bottom view of a car-truck with my coupling attached.

Figure 5 is a sectional view of the arrow-head arrangement for link, and the same in position for coupling to draw-heads of the ordinary construction.

Figure 6 is a front view of the supporting stirrup, with a cross-section of the draw-bars.

Figure 7 is a top view of the link to be used with my improved draw-head.

Similar letters of reference indicate corresponding parts.

In fig. 1 of the drawing—

a represents the arrow-head, which is attached to and between the parallel bars *h*, which bars are connected with the bottom of the car in any suitable manner, allowing of sufficient vertical motion to disengage the arrow-heads and thus uncouple the cars.

t t are bumpers attached to or forming part of the parallel bars *h h*.

S is a lifting-stirrup attached to the parallel bars, for uncoupling the draw-heads.

i is a supporting stirrup.

In fig. 5 *p* represents the link, and
c, the pin for coupling to the draw-heads in ordinary use.

Operation.

The draw-head *a* is supported in position by the stirrup *i*, which is attached at some distance from the front of the car, and which is inclined to admit of a certain amount of elasticity, and is also curved at its

lower or outward end, to permit of a lateral motion of the draw-head, and yet return it to its proper position by gravitation, when relieved from side-pressure.

Upon the approach of two cars fitted with my coupling, the inclined sides meet, and one of the draw-heads is elevated until the arrow-heads pass each other, when the upper one faces, and the cars are coupled, the bumpers *t t* receiving the shock of concussion, and transmitting the same to the ordinary spring-box now in general use.

For uncoupling the cars I use a lifting-stirrup *s*, pivoted on each side of the parallel bars *h h* to the bumpers *t t*, which permits the passage of the opposing draw-head, and secures the application of the lifting force at the most advantageous point, as well, by its attachment to both sides of the draw-head, prevents a tendency to rotation.

The coupling-head *a* is slotted, for the purpose of admitting the link *p*, which is so constructed as to be entirely withdrawn and secured within the draw-head by the pin *c* passing through a hole in its center, when it is intended that two of my couplers shall act together, and is protruded, as shown in fig. 5, when it is desirable to use one of my couplers in connection with the draw-head now in ordinary use.

The link *p* is so constructed with a slot at one end as to permit of its entering and being fastened in the ordinary draw-head, yet prevents the same from coming in contact with my coupler.

Having thus fully described my invention,

What I claim as new, and desire to secure by Letters Patent, is—

1. The combination of the arrow-head *a* with the bars *h h* and the bumpers *t t*, constructed and arranged substantially as described, and for the purposes set forth.

2. The combination of the draw-bars *h h* with the supporting curved and inclined stirrup *i*, arranged substantially as described, and for the purposes set forth.

3. The combination of the stirrup *s* with the bumpers *t t* and the bars *h h* and heads *a a*, substantially as described, and for the purposes set forth.

4. The combination of the link or tongue *p*, constructed as described, with the arrow-head *a*, slotted as described, for the purposes set forth.

EDWARD D. THOMPSON.
